UNITED STATES PATENT OFFICE.

OTTO WILHELM, OF FELDMEILEN, NEAR ZURICH, SWITZERLAND, ASSIGNEE TO
EDOLOF WOLLE, OF LEIPZIG, GERMANY.

BETON OR CONCRETE SLEEPER WITH RESILIENT RAIL-SUPPORTS.

1,017,028.

Specification of Letters Patent. Patented Feb. 13, 1912.

Application filed February 23, 1910. Serial No. 545,467.

To all whom it may concern:

Be it known that I, OTTO WILHELM, a subject of the German Emperor, and residing at Feldmeilen, near Zurich, Switzerland, have invented certain new and useful Improvements in Improved Beton or Concrete Sleepers with Resilient Rail-Supports, of which the following is a specification.

In the ferro-concrete or reinforced beton railway sleepers hitherto made, dowels of wood or other organic substance are inserted for fixing the rail spikes or screws. Efforts have also been made to overcome the disadvantage of the hardness, rigidity and brittleness of the beton or concrete support by means of elastic or resilient underlays or insertions, for which also only vegetable substances were employed which are perishable and not permanent or constant as regards volume. As these do not form a firm connection with the beton of the body of the sleeper, they represent an insertion which divides the body of the sleeper and is injurious to it. The strength of the railway sleepers is thus reduced. A destruction of the iron insertions soon takes place, and a loosening of the means of attachment embedded in the perishable substances.

Now this invention has for its object a method of making a strong ferro-concrete or reinforced beton railway sleeper formed as a longitudinal or transverse sleeper, which avoids the disadvantages hereinbefore mentioned.

The invention consists in that part only of the sleeper, which serves as support for the rail foot, or a foundation plate for the rail, being formed of a mixture of cement or beton with mineral, silicate containing, fibrous material, such as asbestos, slag wool or the like, or of several of these substances together in suitable proportions to one another. The support thus formed for the rail constitutes an elastic and at the same time non-perishable and extremely strong rail support, which is invariable as regards volume and combines with the surrounding beton in such a thorough and permanent manner, that an indestructible homogeneous and monolithic sleeper body is formed which is not liable to deterioration by the weather.

This resilient rail support forming a coherent whole with the concrete sleeper, is also capable of being operated on in any way; it may be sawed, nailed, bored,

plugged, cut and has great tenacity or toughness. Screws (treenails) may be screwed into it without difficulty, after preliminary boring, and find an excellent hold in the asbestos beton support. Means of attachment for the rail foot inserted in any other way, also find an equally good hold, while the kind and form of these means of attachment may be very different.

Even if theoretically beton sleepers of the improved kind without iron insertions, are possible, for practical reasons iron reinforcements should be generally employed for increasing the tractional and compression strength, the special forms of which reinforcements, however, are of ordinary or any suitable nature and are directed according to the actual requirements of each case.

The improved beton sleeper with elastic rail support may be made on a wholesale scale in a factory and be portable, but it may also be made on the spot at which it is to be used, by ramming suitable mixtures of beton and asbestos beton down on the section of track in molds or framework boxes which are removed when it is hardened, which forms when hardened a monolithic sleeper body. Ready formed sockets of asbestos beton or the like may, however, also be directly formed under the rail feet, connected with one another by anchors, and then formed into a monolithic sleeper body by interpolating beton between them or by filling in from the sides beton or ferro-concrete.

My invention will be more fully described in connection with the accompanying drawing and will be more particularly pointed out in and by the appended claims.

In the drawing: Figure 1 is a longitudinal sectional view of a sleeper, showing one embodiment of my invention, and illustrating the rails thereon in section. Fig. 2 is a view similar to Fig. 1. Fig. 3 is a cross-sectional view of the sleeper showing one form of anchorage means in connection therewith. Fig. 4 is a sectional view of a portable rail foot socket and Fig. 5 is an elevation thereof.

Like characters of reference designate similar parts throughout the different figures of the drawing.

Fig. 1 shows a sleeper, which for the sake of economy of material is provided, for instance with a depression or recess 1. Such depressions may be formed at the middle

part and at the ends of the sleeper, also at the sides and underneath. The resilient rail support 2 extends on the right hand side of the figure down to the underside of the body 3 of the sleeper; on the left hand side, a form of construction is shown in which it does not extend quite to the underside (as is also shown in Fig. 2). On the left hand side of Fig. 1, the rail 4 is secured 10 with its washer or tie plate by means of screws 6 to the resilient rail support 2, while on the right hand side in place of the ordinary washer or under plate a so-called hooked plate 7 is employed. The rail foot 15 is thus engaged by the hook of the hooked plate on one side, and on the other side held fast by a clamp plate 8. In order that a displacement of the rail relatively to the sleeper may be possible, in this form of construction the screw holes are made as slotted ones, in which the screws 6 are inserted by means of lining pieces, which are arranged to fit closely between the side walls of the said holes and may be made of various 20 lengths. On the left hand side of the rail (Fig. 1, right hand side), the clamp plate 8 is formed as such a removable lining. In order further to strengthen the resilient rail support against the screws 6 breaking away, 25 spirals 9 of wire or sheet metal are embedded, as shown on the right hand side in Fig. 1. As shown in Fig. 3 on a somewhat enlarged scale (the figure being a cross section of the sleeper and the asbestos-beton 30 support 2) narrower spirals 10 may also be employed, which fit closely to the screw thread and are embedded with the screws before the beton sets, whereupon the screws 35 are withdrawn after the beton sets.

40 In Fig. 2, on both sides, irons 11 are anchored in the asbestos beton 2 by means of spreading arms 12, to which irons the rail 4 is attached in any ordinary way. On the left hand side of Fig. 2, this is done by 45 means of foundation plates or washer plates 5, and headed screws 13, which are firmly but removably screwed into the anchor irons 11. In the right hand side of Fig. 2, a hooked plate 7 is employed, which can engage 50 beneath the anchored iron 11 on one side of the rail by means of a projection 14, while on the other side of the rail the attachment takes place by means of a removable nut and screw 13.

55 Figs. 4 and 5 show in a section and elevation a portable rail foot socket 2 of asbestos beton. This socket is erected on the road bed, the track is laid on it, iron reinforcements are passed through the perforations 60 15 provided for this purpose, and then cemented in, and finally the other part of the sleeper is rammed down in molding boxes. The sides 16 of the socket may be straight or hook-shaped, or made in the 65 form of steps, as shown in Fig. 4, and they

are preferably roughened or grooved to allow of a better connection with the beton sleeper. In Figs. 4 and 5 it is also shown how iron reinforcements 17 may be inserted in the sleeper or socket during the concreting, in order to enable the rail to be attached thereto by means of screws or in other suitable manner. Instead of the Z-profile shown, any other suitable profile may of course be employed, or bent, perforated, 70 or imperforate plates may be employed 75 therefor.

In conclusion, it must be again stated that the form of the iron reinforcements of the beton sleeper and the choice of the 80 means of attachment for the rail may be any suitable one.

While I have herein shown and described my invention in the embodiments shown in the drawing, it will be understood that I 85 do not wish to be limited thereto except for such limitations as the claims import.

Having now particularly described and ascertained the nature of the said invention and in what manner the same is to be performed, I declare that what I claim is:—

1. A concrete sleeper for rails comprising central and end parts composed of solid concrete, and bodies composed of an elastic mixture of fibrous and a cement-like material hardened with the concrete and forming with the central and end concrete parts an integral and congruous, composite mass, the said elastic bodies being disposed only at the rail supporting parts of the sleeper and being co-extensive with the rails and not extending laterally of the rails to an appreciable extent.

2. A concrete sleeper for rails comprising a body portion of concrete, and bodies composed of an elastic mixture of cement-like and asbestos-like substance hardened with the concrete sleeper and forming therewith an integral congruous, composite mass, the said elastic bodies being disposed only at those points of the sleeper on which the rails are supported and not extending laterally of the rails to an appreciable extent, substantially as set forth and shown.

3. A concrete sleeper for rails comprising a body portion wherein the ends and central parts are composed of concrete, and bodies composed of an elastic mixture of cement-like and fibrous substance constituting, with the concrete ends and central parts, an integral congruous, composite mass, the said elastic bodies being disposed only at rail supporting parts of the sleeper and being coextensive in width with the rail and not extending laterally of the rail to an appreciable extent.

4. A concrete sleeper for rails comprising a body portion of concrete, bodies composed of an elastic mixture of cement-like and fibrous substance constituting, with the con-

crete sleeper an integral congruous, composite mass, said bodies being flush with the upper face of the sleeper and extending downwardly therein to at least half the depth thereof, the said elastic bodies being coextensive in width with respect to the width of the rails but not extending laterally of the rails to an appreciable extent.

5. A sleeper for rails comprising a body portion composed of concrete, and bodies composed of a heterogeneous elastic mixture hardened with the concrete and forming with the body portion a congruous, composite mass, said bodies being disposed only 10 at the rail supporting parts of the sleeper and not extending laterally of the rails to an appreciable extent.

6. A concrete sleeper for rails comprising a body portion of concrete, and separate and distinct bodies composed of an elastic mixture which is invariable as to volume with respect to climatic conditions, said bodies being united with the concrete body to form an integral composite mass 20 therewith, said bodies being disposed only at the rail supporting portions of the sleeper and not extending laterally of the rails to an appreciable extent.

7. A concrete sleeper for rails comprising a body portion of concrete, and separate 30 and distinct bodies of a heterogeneous initially soft elastic mixture disposed in said

body when the material of the concrete sleeper and the material of said elastic bodies are soft and both being allowed to 35 simultaneously set to form a composite monolithic mass, said elastic bodies being disposed and only extending abreast of the rail supporting parts of the sleeper and not laterally of the rails to an appreciable extent.

8. In a concrete sleeper for rails comprising a body portion of concrete, and separate bodies of an initially soft elastic material 40 united with the concrete body to form an integral composite mass therewith, said bodies being disposed only at the rail supporting portions of the sleeper and not extending laterally thereof to an appreciable extent.

9. A concrete sleeper for rails comprising a body portion of concrete, and separate bodies of an elastic material united with the concrete body to form an integral composite mass therewith, said bodies being disposed only at the rail supporting portions 50 of the sleeper and not extending laterally thereof to an appreciable extent.

In witness whereof I have hereunto set my hand in presence of two witnesses.

OTTO WILHELM.
